M. M. Paulsen Atty.

UNITED STATES PATENT OFFICE

VAINO EMIL LEHTO, OF EVANSVILLE, INDIANA

RASP OR FILE

Application filed January 16, 1929. Serial No. 332,929.

Rasps or files in the course of time become worn and lose their effectiveness.

The object of my invention is to provide an improved rasp or file having removable and interchangeable teeth, thereby enabling the user to remove any tooth which becomes worn or damaged and to replace any or all of the teeth with others and also permitting the same holder to be employed for teeth of different kinds or sizes.

The invention embodies a backing or holder having an undercut groove or overhanging lips, independent teeth removably engaged with the undercut groove or overhanging lips, and locking means for holding the teeth against displacement.

Different kinds of teeth may be used in the same holder at different times, enabling the tool to be changed from a rasp to a file or vice-versa.

The contour of the teeth may be straight or arcuate or the teeth may extend directly cross-wise, or diagonally, in relation to the length of the holder.

As shown and described, the holder, which is provided with any suitable handle or tang, has a dove-tail groove running lengthwise thereof but it will be understood that overhanging lips of any kind may be used in lieu of a dove-tail groove. For convenience and cheapness of manufacture, the groove may extend through the outer end of the holder and said end be permanently closed by a piece or abutment permanently riveted to the backing and at the other end of the holder, a cross-wedge employed to crowd the independent and removable teeth together to tightly hold them in the groove under the lips, but it will be understood that other means may be employed for that purpose.

In the accompanying drawings:

Figure 1 is a plan view;

Fig. 2 is a longitudinal section through the holder, the teeth being shown in full lines;

Fig. 3 is a plan view of the holder, the wedge and teeth being omitted;

Fig. 4 is a cross section through the holder, showing a tooth in full lines; and

Fig. 5 is an end view of a tooth.

The holder 1 is provided with longitudi-

nally extending lips 2 for engaging the removable teeth. Preferably, the lips are formed by providing a dove-tail seat 3. For convenience and cheapness of manufacture, the seat 3 is formed by cutting inwardly from the outer end of the holder; therefore, there is provided an abutment plate or strip 4 which is suitably secured at 5, as by rivets for instance, which closes the outer end of the seat 3.

Extending cross-wise of the inner end of the seat 3, is a tapered cross groove 6 which is adapted to receive a wedge 7 which is driven into said groove 6 for the purpose of holding the removable teeth 8 crowded against the abutment 4 when said teeth have their ends engaged under the lips 2.

The removable teeth may be of any shape desired and their lengths may extend directly cross-wise of the holder or at an inclination thereto. The teeth may have straight crests or cutting edges or they may be arcuate, as with a half round file or rasp. The teeth may be of any degree of fineness or coarseness. Each tooth has a body 9 whose ends fit under the lips 2 and when the seat 3 is of the dove-tail form disclosed, these bodies 9 are of dove-tail form to fit the seat and project under the lips 2. The teeth have their ends 10 overlying the lips 2 so that the teeth extend the full width of the holder 1.

The tang or handle 11 may be of any desired shape but, as shown, it is offset from the plane of the holder 1 so that it may be readily grasped without danger of the knuckles or fingers of the user coming in contact with the work.

Having laterally slid the teeth 8 into the cross groove 6, they are passed along the seat 3 until the holder is full, whereupon the wedge 7 is driven into the groove 6, thus forcing the teeth firmly against the abutment 4 so that they cannot twist or shift.

Whenever a tooth is broken or needs sharpening, it can be taken out by removing the wedge 7 and taking out the various teeth until the injured or worn tooth or teeth are reached. Obviously, teeth of any inclination, size, or shape, may be used in the holder 1.

What I claim is:

A rasp or file comprising a holder having a seat extending lengthwise thereof provided at its outer end with an attached abutment and at its inner end with a cross groove 5 tapered from one end to its other end and opening out through both sides of the holder, removable teeth whose bodies are received in the seat and which are of lesser width than the cross groove so that their bodies may be 10 inserted in said cross groove for introduction into the seat, or, for removal from said seat, and a removable wedge driven into said cross groove for holding the bodies of the teeth in the said seat, said wedge having its outer 15 face lying below the teeth to prevent interference with the teeth when the rasp or file is in use and to prevent injury to the hands of the user.

In testimony whereof I affix my signature.
